UNITED STATES PATENT OFFICE

145,104

DESIGN FOR A COMBINATION BOOKCASE AND DESK

Yubie W. Rogers, St. Louis, Mo.

Application July 9, 1945, Serial No. 120,598

Term of patent 7 years

(Cl. D33—7)

To all whom it may concern:

Be it known that I, Yubie W. Rogers, a citizen of the United States, residing at 117 South Leonard Avenue, city of St. Louis, in the county of St. Louis and State of Missouri, have invented a new, original, and ornamental Design for a Combination Book-Case and Desk, of which the following is a specification, reference being had to the accompanying drawings, forming part thereof.

In the drawings:

Fig. 1 is a front elevational view of a combination book-case and desk, with the unit closed, and showing my new design.

Fig. 2 is a side elevational view looking towards the right of Figure 1.

Fig. 3 is a side elevational view looking towards

the left of Figure 1, and showing the unit opened for use as a desk, and with the book-case door in lowered position.

Fig. 4 is a top plan view of the unit as shown in Figure 1.

Fig. 5 is a rear elevational view of the unit as shown in Figure 1.

Figure 6 is a front perspective view of the unit with the book-case door in lowered position.

Figure 7 is a rear perspective view thereof as it appears when used as a desk.

The characteristic features of my new design are shown by means of full lines in the drawings.

I claim:

The ornamental design for a combination book-case and desk, as shown and described.

YUBIE W. ROGERS.
